UNITED STATES PATENT OFFICE.

MOURICE SCHLESINGER, OF CLEVELAND, OHIO.

STOP INDICATOR.

Application filed April 20, 1926. Serial No. 103,261.

The invention relates to indicators for use upon street cars, busses, and the like for designating the next stop of the vehicle by number or name of the street or station; the mechanism being arranged to be operated to display successive stop designations by a cord arranged to be pulled by the motorman or conductor as the vehicle approaches each stop.

- 10 The object of the improvement is to provide an indicating apparatus of this character which includes a web or band arranged to be unwound from one roll upon another roll, the propelling power being applied directly to the band by means of a pair of driven friction rollers engaging opposite sides of the band whereby the band is moved a uniform distance with each operation of the mechanism, a spring being operatively connected to the roll upon which the band is wound, keeping the same under tension to take up slack in the band and tension means being provided upon the other roll for preventing the same from unwinding too rapidly; means being provided for manually unwinding the band and winding it upon the other roll at the end of each trip or run of the vehicle, this winding means automatically tensioning the spring upon the winding roll; the propelling rolls being driven by a chain gear which is intermittently operated by a detent carried upon a slide arranged to be moved in one direction by the pull cord against a coil spring resistance for returning the slide to the initial position; means being provided whereby if the vehicle is stopped en route and required to return to the starting point the band may be quickly wound upon the upper or winding roll; means being also provided whereby the vehicle may diverge at any point and travel over a different route, two or more parallel columns of stop designations being printed upon the band and a shutter or door being provided to conceal either column when the vehicle is traveling over the route shown in the other column.

The above and ancillary objects may be attained by constructing the mechanism in the manner illustrated in the accompanying drawings, in which

Fig. 1, is a view of the interior of the case

or box in which the mechanism is enclosed, the back plate being removed to disclose the mechanism;

Fig. 2, a transverse sectional view through the case and mechanism taken substantially on the line 2—2, Fig. 1;

Fig. 3, a similar view taken substantially on the line 3—3, Figure 1;

Fig. 4, a transverse sectional view through the slide and detent on the line 4—4, Fig. 2;

Fig. 5, a section through one journal of the unwinding roll taken on the line 5—5, Figure 1;

Fig. 6, a similar view of the other journal of the unwinding roll taken on the line 6—6, Figure 1;

Fig. 7, a detail sectional view through the winding roll, showing the means for attaching the web or band thereto;

Fig. 8, a front elevation of the indicator showing the manner of displaying each stop designation;

Fig. 9, a similar view showing the web or band designed for two different routes, one of the shutters or slides being closed over the unused portion of the band;

Fig. 10, a fragmentary detail view of a portion of the web or band and

Fig. 11, a fragmentary detail view of a portion of the web or band having designations for an entire round trip of a given route, the view being taken at the designations near the end of the route.

Similar numerals of reference indicate corresponding parts throughout the drawings.

The mechanism is enclosed in a case or box, indicated generally at 1 and arranged to be mounted in a conspicuous place at the front end of the vehicle so that the stop or station designations displayed through the opening 2, in the front wall of the case or box, may be easily seen by the passengers in the vehicle.

This box or case may be made of wood and provided with a metal plate 3 upon the interior of each end wall to support the mechanism.

The stop designations are printed or otherwise impressed upon the web or band 4, which is normally rolled upon the unwinding roll 5 and arranged to be unwound from

the roll 5 upon the winding roll 6, as the mechanism is operated, passing the web or band intermittently across the opening 2 in the case.

5 Each of the rolls 5 and 6 is in the form of a spool provided with enlarged peripheral flanges 7 at its ends and each of these rolls may be termed an idler as it is loosely journaled within the case.

10 The web or band 4 is arranged to be propelled by means of a pair of co-acting rollers 8 and 8' provided with friction surfaces of rubber or the like as shown at 9 and 9', between which the band is passed. The rubber 15 surfaces are preferably vulcanized to the rollers.

These friction propelling rollers are journaled at opposite ends in the end walls in the case, and the roll 8 is geared preferably 20 at each end, by means of the pinions 10, with gears 11 fixed upon a rotating shaft 12 upon which is also fixed a sprocket wheel 13 over which an endless sprocket chain 14 is located.

The roller 8' is preferably journaled in a 25 horizontal slot 8^a in the end walls of the case, and the shaft 8' is provided with adjustable means for normally exerting a desired pressure between the rolls 8 and 8' for propelling the band 4 which passes upward from the 30 unwinding roll 5 between the propelling rollers and then over idle rolls or shafts 11^a located near the opening 2 and winding roll 6 upon which the band is wound as it is propelled past the opening 2.

35 The means for adjusting the pressure between the rollers 8 and 8' may include wedge slides 8^b provided with outwardly extending shafts 8^c passing through preferably vertically extending slots 8^d in each end wall of 40 the case, the shafts 8^c being provided at their outer ends with knobs 8^e.

When the wedged slides 8^b are in the position illustrated in Figs. 2 and 3, pressure 45 between the propelling rolls is applied to enable propulsion of the band as aforesaid.

When it is desired to unwind the band from the rolls 6 as hereafter to be described, the knobs 8^b may be moved upwards, thereby 50 relieving the pressure between the rolls 8 and 8'.

The sprocket chain 14, passes over idle sprockets 15 and 16 which for the purpose of convenience may be loosely journaled upon the shafts of the unwinding and winding 55 rolls 5 and 6 respectively.

For the purpose of taking up slack in the sprocket chain an adjustably mounted pulley 17 may be provided, being arranged to be moved upon its support 17^a fixed in adjusted 60 position to hold the chain taut as best shown in Fig. 2.

The mechanism for operating this sprocket chain to drive the propelling rollers comprises a detent 18, pivotally mounted as at

19, upon a slide 20 mounted for reciprocation within the guide channel 21. A cord 22 is connected to the lower portion of the slide and extended over a pulley 23, being connected at its extremity to a coil spring 24 fastened at its free end, as at 25, to the bottom 70 wall of the case.

The pivoted detent is connected, at its lower end, to a coil spring 26, the other end of which is connected to the slide, tending to urge the detent into the position shown in dotted lines, in Fig. 2, against the stop pin 27, upon the slide. When held in the full line position, shown in Fig. 2, by means of the spring 24, the detent 18 engages the stop pin 28, in the adjacent end wall of the 80 case, holding the extremity of the detent away from the path of the sprocket chain 14.

A cord 29 is fixed to the upper end of the slide 20 and passes over a pulley 30 being extended to any suitable position where it may be accessible to the motorman or conductor.

For the purpose of preventing the belt from unwinding too rapidly from the lower or unwinding roll 5 one or more curved tension springs 31 may engage the same as illustrated in Figs. 1 and 3; and for the purpose of winding the band upon the upper or winding roll 6, as it is propelled upward by the friction propelling rollers 8 and 8', a helical spring 32 is provided.

This spring may be located within a casing 33 and operatively connected to the shaft 34 of the large sprocket wheel 35, a sprocket chain 35^a being located around this wheel and around the smaller sprocket wheel 36 100 mounted upon the shaft of the upper or winding roll 6.

This spring 32 is normally held under tension, as will be later described, and thus tends to urge the sprocket wheel 35 in the direction of the arrow, shown in Fig. 3, thus winding the web or band upon the winding roll 6 as it is propelled upward by means of the propelling rollers 8 and 8'.

The end of this web or band may be connected to the roll 6 in the manner shown in Fig. 7, an aperture 37 being provided in the end portion of the band for engagement with a stud or pin 38 extended from the flat face 39 of the roll.

The lower or unwinding roll 5 is preferably detachably mounted in its journal bearings as shown in Figs. 5 and 6. This may be accomplished by providing a stud 40 in one end plate upon which is journaled the sprocket wheel 15, normally urged outward upon the stud by the spring 41. A hub 42 is provided upon this sprocket wheel and receives the reduced spindle 43 upon the adjacent end of the unwinding roll 5. A 120 similar stud 44 is carried by the other end plate and the sleeve 45 is journaled thereon and provided with a squared aperture 46 to

receive the squared shank 47 upon the other end of the roll 5.

A pinion 48 is fixed upon the sleeve 45 and meshes with the gear 49 mounted upon a shaft 50, journaled through the adjacent end wall, and provided with a crank handle 51 by means of which the band or web may be rewound upon the lower roll 5 after the vehicle has covered its route.

10 As the band is thus rewound, the spring 32, through the sprockets 35 and 36 and sprocket chain 35^a is rewound, being thus placed under tension ready for further operation.

15 For the purpose of quickly winding the band upon the upper or winding roll 6, in the event that the vehicle is stopped en route, before it reaches its destination and is required to return to the starting point,

20 a handle crank 52 may be provided upon the shaft of the upper winding roll 6. In order to cover a situation where a vehicle may travel two alternate branch routes, the band or web 4 may have printed thereon a

25 single column of stop designations, as indicated at 53, showing the stops upon the route up to the branch, after which two or more parallel columns, as indicated at 54 and 55, are provided showing the stops along each 30 branch route. A shutter or door 56 is provided, upon the front face of the case, to cover each half of the opening 2, thus providing means whereby one column may be concealed when the vehicle is travelling over

35 the branch route shown in the other column.

As shown in Fig. 9, the car is travelling over the branch route shown on the column 54 and the door or shutter provided for the other side of the opening is in closed position, thus covering the stop designations in the column 55.

40 However, when the car is travelling over the main route, as shown in Fig. 8, both of the shutters or doors are left in open position, thus displaying the stop designations upon the main route.

It is the intention to provide upon the band or web all of the stop designations throughout an entire round trip of the vehicle. Fig. 11 is a fragmentary view of the

50 web and the designations near and at the end of the route illustrating the method of applying the designations in order to provide the band or web with all of the stop designations throughout an entire round trip. As illustrated the route ends at street No. 132 which designation will be approximately in the middle of the band, the designations up to No. 132 being arranged on the band in progressive sequence and in regressive sequence beyond the designation 132.

55 The vehicle thus starts from a central starting point and travels away therefrom to the extreme end of the route, and then returns back to the starting point during which

the indicating device requires no attention excepting that the motorman or conductor pulls the cord 29 between stops.

With each pull of the cord the slide 20 is moved upward into the dotted line position, 70 shown in Fig. 2, the spring 26 pulling the detent 18 into the dotted line position shown in said figure, into engagement with the stop pin 27, engaging the detent with the sprocket chain 14 and moving this chain 75 a uniform distance with each operation, the stop pin 57 limiting the upward movement of the slide.

In order to call attention to the operation of the indicator an audible signal, such as 80 the bell 58, may be provided, the spring pressed tapper 59 being tripped by the outer end of the detent 18 to ring the bell with each upward operation of the slide.

As the sprocket chain 14 is moved a uniform distance, with each pull of the cord, the positively driven friction propelling rollers 8 and 8' move the web or band upward a uniform distance with each operation. 85

90 As the web or band is moved upward with each operation of the cord the tension spring 32, acting upon the upper or winding roll 6 will roll the web tightly upon said upper roll while the tension springs 31, engaging the lower or unwinding roll will prevent the same from unwinding too rapidly, thus holding the entire band taut. 95

95 As the pull upon the cord is released, the coil spring 24 returns the slide to the initial position, shown in full lines in Fig. 2, in which the detent is swung out of engagement with the chain and ready for another operation. 100

105 When the car has completed a round trip, and returned to the starting point, the entire band is wound backwards upon the unwinding roll 5, by means of the handle crank 51, and it will be seen that this winding operation will rotate the shaft 34 in a direction to rewind the tension spring 32, thus placing the mechanism in position for another round trip. 110

I claim:

1. An indicator including a winding roll 115 and an unwinding roll, a band having its ends connected to said rolls, a pair of positively driven friction propelling rollers engaging the band, an endless chain operatively connected to said propelling rollers, 120 a slide mounted adjacent to said chain, a detent movably mounted upon the slide, means for normally holding the detent out of engagement with the chain, means for moving the slide a uniform distance with each operation and means for automatically engaging the detent with the chain upon each operation of the slide. 125

2. An indicator including a winding roll 130 and an unwinding roll, a band having its

- ends connected to said rolls, a pair of positively driven friction propelling rollers engaging the band, an endless chain operatively connected to said propelling rollers, 5 a slide mounted adjacent to said chain, a detent pivotally mounted upon the slide, means for normally holding the detent out of engagement with the chain, means for moving the slide a uniform distance with 10 each operation and means for automatically engaging the detent with the chain upon each operation of the slide.
3. An indicator including a winding roll and an unwinding roll, a band having its 15 ends connected to said rolls, a pair of positively driven friction propelling rollers engaging the band, an endless chain operatively connected to said propelling rollers, a slide mounted adjacent to said chain, 20 a detent movably mounted upon the slide, means for normally holding the detent out of engagement with the chain, means for moving the slide a uniform distance with each operation, means for automatically engaging the detent with the chain upon each 25 operation of the slide and means for moving the slide back to the initial position without moving the chain.
4. An indicator including a winding roll and an unwinding roll, a band having its 30 ends connected to said rolls, a pair of positively driven friction propelling rollers engaging the band, an endless chain operatively connected to said propelling rollers, 35 a slide mounted adjacent to said chain, a detent pivotally mounted upon the slide, means for normally holding the detent out of engagement with the chain, means for moving the slide a uniform distance with 40 each operation, means for automatically engaging the detent with the chain upon

each operation of the slide and means for moving the slide back to the initial position without moving the chain.

5. An indicator including a winding roll 45 and an unwinding roll, a band having its ends connected to said rolls, a pair of positively driven friction propelling rollers engaging the band, an endless chain operatively connected to said propelling rollers, a slide mounted adjacent to said chain, a 50 detent movably mounted upon the slide, means for normally holding the detent out of engagement with the chain, means for moving the slide a uniform distance with 55 each operation, means for automatically engaging the detent with the chain upon each operation of the slide, an audible signal, and means upon the detent for operating the audible signal with each operation of the 60 slide.

6. An indicator including a winding roll and an unwinding roll, a band having its 65 ends connected to said rolls, a pair of positively driven friction propelling rollers engaging the band, an endless chain operatively connected to said propelling rollers, a slide mounted adjacent to said chain, a detent pivotally mounted upon the slide, tension means for normally holding the slide 70 at one end of its travel, a spring connected to the slide and detent for normally urging the detent into engagement with the chain, means acting against the spring for holding the detent out of engagement with the chain 75 when the slide is in the normal position and means for moving the slide a uniform distance with each operation.

In testimony that I claim the above, I have hereunto subscribed my name.

MOURICE SCHLESINGER.
